UNITED STATES PATENT OFFICE.

SAMUEL J. BLUMENTHAL, OF BROOKLYN, NEW YORK.

SURGICAL INSTRUMENT.

Application filed March 15, 1924. Serial No. 699,406.

This invention relates to surgical instruments and particularly what are known as sponge holders; and the object of the invention is to provide an instrument of the 5 class specified with improved means for supporting a sponge or other body and for retaining the same against displacement when supported in connection with the instrument; a further object being to provide 10 means for retaining the sponge supporting body permanently in connection with the instrument; a still further object being to provide an instrument in connection with which supporting bodies of different shapes 15 or forms may be mounted; and with these and other objects in view, the invention consists in an instrument of the class and for the purpose specified, which is simple in construction, efficient in use and which is constructed as hereinafter described and claimed.

The invention is fully disclosed in the following specification, of which the accompanying drawing forms a part, in which the 25 separate parts of my improvement are designated by suitable reference characters in each of the views, and in which:

Fig. 1 is a side view of an instrument made according to my invention and indicating the method of its use.

Fig. 2 is a section on the line 2—2 of Fig. 1 with part of the construction shown in Fig. 1, omitted.

Fig. 3 is a detail view of a modified form 35 of supporting body which I may employ.

Fig. 4 is a view similar to Fig. 1 but showing only a part of the construction and showing a modification; and,

Fig. 5 is a view similar to Fig. 3 but 40 showing a modified form of supporting body adapted for use in the instrument shown in Fig. 4.

In Fig. 1 of the drawing, I have shown one form of instrument made according to 45 my invention and comprising two handle members 10 and 11 pivoted together as shown at 12 and provided at their free ends with loops 13 to receive the fingers of a hand, and the handle members are adjustably interlocked as shown at 14 in the usual manner 50 in instruments of the class under consideration. The handle members 10 and 11 project beyond the pivot 12 in the form of jaw members 10^a and 11^a said handle members 55 being crossed at the pivotal connection in the manner shown and said jaw members are

provided with inter-meshing jaws 10^b and 11^b at their free ends.

A sponge supporting member 15 comprising a rod 16 and an elliptical cylindrical body 17 is coupled with the tool the coupling being formed by passing the pivot pin or screw 12 through a loop or eye 18 at one end of the rod 16. In the construction shown in Figs. 1 and 2, the attached end of the rod 16 is located between the separate handle members 10 and 11 where pivoted together and said rod extends in substantially parallel relation to the longitudinal plane of the instrument as does also the body 17. The 65 body 17 has a neck portion 17^a which is adapted to fit within the jaws 10^b and 11^b and in the use of the instrument shown in Figs. 1 and 2, a piece of absorbent cotton, gauze or other material, commonly called 70 in the profession a sponge, 19 is passed around the body 17 and the neck 17^a thereof when the jaw members 10^a and 11^a are in an open position after which the handle members are operated to move the jaw members 80 into operative position to firmly grasp and retain the fibrous covering 19 in position upon the body 17 and against displacement from the instrument, it being understood 85 that the jaw members 10^a and 11^a are locked under tension by the interlocking means 14 on the handle members 10 and 11. Heretofore, it has been customary to grasp a piece 90 of antiseptic cotton, gauze or like material between two jaw members of predetermined shape, but with this construction, parts of the jaw members were exposed, and it has been experienced that the antiseptic cotton, gauze or the like has been displaced from the 95 instrument, causing considerable trouble to the surgeon using the same. With my construction, the above objectionable features are obviated.

In Fig. 3 of the drawing, I have shown a slight modification of the construction shown 100 in Figs. 1 and 2, and particularly the member 15 in which the body 17 and neck portion 17^a are curved with reference to the rod 16, thus offsetting the body 17 with 105 reference to the plane of the instrument which would be desirable in some uses thereof.

In Fig. 4 of the drawing, I have shown another modification in which the jaw members 10^a and 11^a are curved rather than 110 straight as shown in Fig. 1 of the drawing, and with this construction the rod 16 or the

member 15 is curved to correspond with the curvature of the jaw members 10^a and 11^a and the body 17 and neck 17^a are curved to correspond with the curvature of the rod 16.

In Fig. 5 of the drawing, I have shown a modification of the construction of the member 15, in which a flat disk-shaped body 17^b is substituted for the elliptical, cylindrical body 17. The shape of the body 17^b is preferably elliptical in form but any shape of body may be employed other than those herein shown and described, to suit specific uses of the instrument.

The instrument is designed for use by surgeons and others in stopping the flow of blood during surgical operations and primarily for use in such operations as the extraction of tonsils and adenoids and as hereinbefore stated, a body of predetermined anti-septic material such as cotton, gauze or the like is mounted on the supporting body 17 or 17^b and retained in position by the jaws 10^b and 11^b.

It will be noted that the member 15 by reason of its pivotal mounting is capable of movement relatively to the separate jaw members to facilitate the centralizing thereof between said jaw members, and it will be understood that while I have shown certain details of construction for carrying my invention into effect, that I am not necessarily limited to these details and various changes therein and modifications thereof may be made within the scope of the appended claims without departing from the spirit of my invention or sacrificing its advantages.

Having fully described my invention, what I claim as new and desire to secure by Letters Patent, is:—

1. An instrument of the class described comprising relatively movable jaw members having gripping jaws at their free ends, a sponge mounting member supported on the pivot of said jaw members and positioned therebetween, said sponge mounting member being provided beyond said jaws with an enlarged body on which a sponge is adapted to be mounted, the jaws of said jaw members being adapted to engage said sponge supporting member adjacent the en-

larged body thereon, and said sponge, to retain the sponge against displacement from said body.

2. An instrument of the class described comprising relatively movable jaw members having gripping jaws at their free ends, a sponge mounting member supported on the pivot of said jaw members and positioned therebetween, said sponge mounting member being provided beyond said jaws with an enlarged body on which a sponge is adapted to be mounted, the jaws of said jaw members being adapted to engage said sponge supporting member adjacent the enlarged body thereon, and said sponge, to retain the sponge against displacement from said body, and said jaw members and sponge supporting member being curved.

3. An instrument of the class described comprising relatively movable jaw members having gripping jaws at their free ends, a rod mounted on the pivot of said jaw members and positioned therebetween, the free end portion of said rod projecting beyond the jaws of said jaw members and provided externally thereof with an enlarged sponge supporting body, and the jaws of said jaw members being adapted to engage that portion of a sponge encircling said rod adjacent said body to hold the sponge against displacement from said body.

4. An instrument of the class described comprising relatively movable jaw members having gripping jaws at their free ends, a rod mounted on the pivot of said jaw members and positioned therebetween, the free end portion of said rod projecting beyond the jaws of said jaw members and provided externally thereof with an enlarged sponge supporting body, the jaws of said jaw members being adapted to engage that portion of a sponge encircling said rod adjacent said body to hold the sponge against displacement from said body, and the circumferential dimensions of the jaw end portion of said jaw members being less than the corresponding dimensions of said enlarged body.

In testimony that I claim the foregoing as my invention I have signed my name this 14th day of March, 1924.

SAMUEL J. BLUMENTHAL.
